UNITED STATES PATENT OFFICE.

ROBERT DELAUNAY-BELLEVILLE, OF ST. DENIS, SEINE, FRANCE, ASSIGNOR TO SOCIÉTÉ ANONYME DES ÉTABLISSEMENTS DELAUNAY-BELLEVILLE, OF ST. DENIS, SEINE, FRANCE, A CORPORATION OF FRANCE.

VALVE.

1,062,213.

Specification of Letters Patent.

Patented May 20, 1913.

Application filed February 20, 1911. Serial No. 609,777.

To all whom it may concern:

Be it known that I, ROBERT DELAUNAY-BELLEVILLE, citizen of the French Republic, residing at St.-Denis, Department of the 5 Seine, in France, have invented certain new and useful Improvements in and Relating to Valves; and I do hereby declare the following to be a full, clear, and exact description of the invention, such as will enable others 10 skilled in the art to which it appertains to make and use the same.

The distributing members of elastic fluid engines should be balanced at least partially to enable them to operate without necessitating excessive efforts of displacement. 15 The realization of this condition entails a very serious inconvenience because in proportion as the balancing is improved leakages increase, the pressure being insufficient 20 for applying the distributor to its seat. An increase in the consumption of the motor fluid and a reduction in the efficiency of the engine results from this. The distributor hereinafter described serves to produce the 25 balancing which is practically necessary for the free operation of the part and also for producing a good joint such as is indispensable for preventing leakages. This result is obtained by loading the distributor while 30 it remains at rest and relieving it at the moment at which it is about to be operated. This distributor comprises a main valve, a cylindrical slide valve and an auxiliary relieving valve.

35 The arrangement embodying the invention is hereinafter described upon the assumption that the motor fluid is steam but it is applicable with all the elastic fluids employed as motor media. It is represented 40 by way of example in the accompanying drawing in which:

Figure 1 is a sectional view of a valve and casing, the cylinder orifice being closed and the valve resting upon its seat. Fig. 2 is a 45 similar sectional view showing the cylinder orifice wide open and Fig. 3 is a similar view showing the valve descending and the cylinder ports already closed but the valve not yet resting on its seat; it closes 50 shoulder to shoulder upon the admission of the steam. Fig. 4 is a sectional view of an exhaust valve embodying the invention. Figs. 5 and 6 are sectional views illustrating details.

The outer portion 1, 1 forms part of the 55 cylinder; the passages 2, 2 conduct the live steam which is introduced into the cylinder through the orifices 3, 3 distributed over the periphery and separated by ribs. The parts 4, 4 housed in a boss in the cylinder constitute the valve holder.

The valve 5, 5 comprises two diameters, and shoulders 6 and 6² are formed on the valve holder 4 and on the valve 5 (Fig. 3) and these shoulders produce the closure; 65 they may be either plane or conical. The upper part of the valve is much elongated and forms a guide. The lower part, which is short, is continued by the ribs 7, 7 the extremities of which are connected by the 70 ring 8; the metal ring 9 which is slit in the manner of piston rings and forms a spring is by means of a nose engaged in the ring 8 and slides with friction in the valve holder 4. The ring 9 is the part obturating the 75 orifices 3 while the upper part of the valve forms an obturation in front of the orifices 10 in the valve holder which register with the passages 2 through which the live steam is supplied. This latter obturation is not 80 complete, however; the steam reaches the valve through one or more small orifices 11 which permit of its access to the valve with the object hereinafter explained. Owing to this construction the valve differs from a 85 slide valve in that it has two closures the ring 9 and the shoulder 6².

In the position illustrated in Fig. 1 the valve rests upon its seat 6 and the steam is 90 unable to pass from the conduit 2 into the orifice 3 in the cylinder. It is only able to penetrate above the valve through the orifices 11 and exert a downward effort upon this valve and by reason of the difference of the diameters this downward effort is 95 more powerful than the upward effort exerted by the steam which is beneath the valve and further the steam beneath the valve exerts less pressure than that exerted by the steam acting downward. Consequently, when the valve is applied to its seat it is not balanced and in order that it 100 may be displaced readily it is necessary to relieve the pressure of steam on the valve. The valve is relieved by lifting the small 105 auxiliary valve 12 by means of its stem 13; owing to its small size this valve makes but little resistance. As soon as this valve 12

is lifted the steam which is able to flow above the valve 5 through the orifices 11 passes through the passages 14 and produces equality of pressure upon the two faces of the valve 5; when this takes place this valve is sufficiently relieved. As the upward movement of the valve 12 continues the stop 15 fixed to the stem 13 comes into contact with the valve 5 and the latter is displaced. At this moment the lower end of the rod 13 uncovers the passages 16, 16 and a certain quantity of live steam enters the expansion cylinder where it increases the pressure of the steam compressed at the end of the stroke of the piston; this facilitates the change in the bearing of the joints before the admission takes place. This operation is especially useful with very great expansions and condensation operation because the steam withheld in the cylinder for the compression has a very small tension. During this small introduction of steam into the cylinder the entire valve mechanism is lifted, the piston-valve uncovers the orifices 10 and the ring 9 then uncovers the orifices 3. The valve reaches the end of its stroke (Fig. 2) and the steam enters through large passages into the cylinder in passing through the orifices 10 into the lower compartment of the valve between the ribs 7 and then into the orifices 3 of the cylinder. The spiral spring 17 is increasingly compressed and it maintains the valve in contact with the stop 15 on the stem which prevents any vibration of the valve 5 and the valve 12 remains open.

Fig. 3 represents the piston-valve at the point of its down stroke at which the closure of the orifices 10 by shoulder 6² of the valve begins; the ring 9 has already closed the orifices 3. The operating member of the valve stem such as a cam or trip gear has forced the stem to descend but the spring 17 which tends to force the valve downward at a greater speed than the stem moves has pressed the valve downward and maintained this valve in contact with the stop 15 in such a manner that the auxiliary valve 12 remains momentarily open. In the position shown in Fig. 3 the valve 5 in its descent shuts in live steam in the space 6'. This steam is compressed and opposes resistance. This produces two results the first being that the valve reaches its position of repose without shock even in the case of trip gear operation; the second result is a momentary stoppage of the valve owing to which the auxiliary valve 12 in completing the downward stroke is able to close because the valve 5 only descends slowly; there is no longer any communication between the upper part and the lower part of the valve and from this moment the pressure of the steam which is in the lower part of the valve diminishes because this steam continues to be admitted to the cylinder where expansion

takes place through the passages 16 which are not obturated until somewhat later by the end of the stem 13. The result is that when the valve 5 rests upon its seat it is applied thereon by the pressure of the live steam upon its upper face, while below there is expanded steam, the pressure of which is less. This valve is therefore loaded both owing to the difference of the sections and owing to the difference of the pressures. The valve has a double obturation one upon the seat 6 of the valve and the other upon the ring 9 which the pressure of the steam although it is somewhat expanded presses against the orifices 3 because the pressure in the cylinder during the expansion and then during the exhaust is much smaller than that of this steam. If a foreign body should become interposed upon the seat between the two bearing surfaces this would not prevent the central valve 12 from being closed because closing takes place before the bearing surfaces 6 and 6² are in contact and as the ring 9 is of sufficient width to obturate the orifices 3 perfectly there would not be any leakage.

Fig. 4 represents the application of the device to an exhaust valve. The numerals which are common to this figure and to the preceding figures designate the same parts or similar parts. The valve holder 4 is fitted into the boss 1 arranged at a suitable part of the cylinder. The upper part of this valve holder is provided with orifices 10' for the discharge of the steam from the cylinder when the valve is lifted. The valve 5 is represented in the closed position upon its seat and the ring 9 covers the discharge orifices 20. When the valve is lifted the steam to be discharged will pass through the orifices 10', enter the interior of the valve 5 and the ring 9 having ascended the steam will escape through the orifices 20 and the passages 21. The auxiliary valve 12 is a relieving valve; it is integral with the operating rod 13; a spiral spring 22 compressed by the member 23 under the influence of the nut 24 screwed onto the rod 13, holds the valve 12 upon its seat when the valve 5 occupies its closed position. Slightly before the exhaust opens the rod 13 is operated, the spring 22 is slightly more compressed and the valve 12 opens. The fluid which is in the cylinder passes beneath the valve 12 and enters the valve 5 through the orifices 25; equilibrium of pressure at once arises between the upper part and the lower part of the valve 5 and the valve is relieved. When the exhaust is finished the valve descends, the steam imprisoned between the bearing surfaces of the valve 5 and of the valve holder 4 exerts its action and the valve 12 closes. There are two closures: by the ring 9 and by the seat 6 of the valve.

Fig. 5 shows at the left side a vertical sec-

tion passing through the slit in the ring 9 in Figs. 1 to 4, and at the right side a horizontal section through the middle of the ring. The ring 9 is mounted in such a manner that its slit is opposite a rib; the nose of this ring is cut away for a small width to right and left of the slit and a snug 26 fixed upon the ring 8 prevents any displacement of the ring 9 relatively to the valve and 10 hence the slit is always adjacent the rib. In this manner no leakage can take place because there is the same pressure above the edge of the ring as below it and the slit in the ring is covered by the rib. Even if the 15 ring 9 is not displaced relatively to the valve however the latter might move upon its seat and bring the slit in the ring opposite an orifice. The following arrangement obviates this defect. Fig. 6 represents at the left side 20 a vertical section on the slit in the ring 9 and the right side a horizontal section through the middle of the ring. The ring 8 is cut away vertically for the reception of the hook 27 which is fitted into the recess 25 and which exactly covers the ring 9 at the slit with slight friction; the nose of the ring 9 is cut to the right and left of the slit and it is the hook 27 which prevents the ring from rotating. With this arrangement the 30 slit is always covered upon the edges of the ring and no leakage can take place whatever the position of the ring relatively to the orifices may be.

I claim:

35 1. In a slide valve, a valve casing provided with a valve seat, a valve to coöperate with said seat, means to allow live steam to exert a seat maintaining pressure on the valve when the same is seated, means operative in the closing movement of the valve to entrap steam between the valve and valve seat before the steam is allowed to exert said pressure on the valve, and means to release said pressure to allow the valve to be unseated.

40 2. In a slide valve, a valve casing provided with upper and lower passages, a main valve guided in said casing, a valve seat to coöperate with said main valve, said main valve having an upper portion and a lower portion adapted to close the upper and lower passages respectively, an auxiliary valve in the upper portion of said main valve, means to operate the main valve, 45 means to entrap steam between said main

valve and said valve seat in the closing of the main valve, the entrapping of the steam enabling the auxiliary valve to be closed, means to allow steam to exert a seat maintaining pressure on said main valve after 60 the closing of the auxiliary valve, and means to open said auxiliary valve to allow said main valve to be unseated.

3. A slide valve comprising a valve casing provided with upper and lower passages, a main valve having upper and lower portions to close said passages, a valve seat to coöperate with said main valve, a valve stem carrying said main valve, an auxiliary valve seat in said main valve, a valve on said stem to coöperate with said auxiliary valve seat, a passage in said casing adapted to be opened and closed by said stem, means to allow live steam to exert a seat maintaining pressure on the main valve when the same is seated, said auxiliary valve constituting means to release said pressure, and means to entrap steam between the main valve and said valve seat when the valve is seating.

4. A slide valve comprising a casing, upper and lower passages in said casing, a main valve having an upper and lower portion to form closures to said passages, a valve stem upon which said main valve is loosely mounted, an auxiliary passage in 85 said casing controlled by said valve stem, a seat in said casing with which the upper portion of the main valve coöperates, an auxiliary valve disposed in said upper portion of the main valve adapted to be operated when said stem makes a stroke in one direction, means to cause said main valve to move in advance of the stem when said stem makes its return stroke to maintain the auxiliary valve in its opened condition, 90 means to entrap a quantity of steam between said main valve and the seat with which it coöperates to check the movement of said main valve and thereby allow the auxiliary valve to close before the stem closes the said 95 auxiliary passage in the casing, and means to allow live steam to exert a seat maintaining pressure on said main valve when seated.

In testimony whereof I affix my signature, in presence of two witnesses.

ROBERT DELAUNAY-BELLEVILLE.
